GARMENT HANGER

William Adelman, Philadelphia, Pa.

Application June 14, 1952, Serial No. 293,498

2 Claims. (Cl. 223—92)

1

The present invention relates to a garment hanger of the type commonly employed for suspending garments in position for display and is concerned primarily with certain improvements involving the provision of means for detachably securing a size tag in position on a hanger where it may be readily seen either by a store attendant or a prospective purchaser.

At the present time, it is common practice in stores engaged in the selling of men's and women's garments, to suspend suits, dresses, coats, and similar garments on hangers which are, in turn, hung on rods or other suitable supports. When a salesman is engaged in displaying garments to prospective purchasers, considerable difficulty is experienced in determining the size of any garment which is supported by any particular hanger. The present invention has as its foremost objective, the provision of a garment hanger which completely eliminates this undesirable factor and makes it possible for the salesman or purchaser to tell at a glance the size of any garment which is suspended from any hanger.

More in detail, the invention has as an object, the provision of a garment hanger which includes a device that is located closely adjacent to the shank of the hook of the hanger and which detachably receives a size tag. In certain instances, the size tag is completely enclosed and the retaining device, therefore, is of a transparent material which permits reading of the size tag through the retaining device.

In its most simplified form the present invention involves the combination of a garment hanger together with a tag retainer in the form of a U-shaped member of transparent material having one side wall which is secured to the garment hanger by an adhesive. The other side wall is maintained in slightly spaced relation with respect to the hanger bar by side flanges and a size tag is adapted to be slipped in between this side wall and the bar of the hanger.

In a slightly modified form of the invention, the tag retainer is made of a transparent, flexible plastic which is adapted to completely enclose the hanger bar and which has a top wall which receives the shank of the hook. This retainer also has one side wall which is maintained in spaced relation with respect to the hanger bar by side flanges. The size tag is slipped in beneath this side wall.

The size tag retainers mentioned above are particularly adapted for use with the conventional garment hanger now meeting with widespread usage and which consists of nothing more than

2

a curved bar having the shank of a hook joined thereto, midway the ends thereof. This bar is generally of wood or a comparable material.

There is also a hanger which is now meeting with an appreciable amount of usage and which is made of plastic. Such a hanger ordinarily includes a central panel to which the shank of the hook is anchored. The present invention also has in view as an object, the provision of a garment hanger of this type in which the central panel is provided on one or both faces with a pair of corner pockets with each pair being adapted to detachably receive a size tag.

Various other more detailed objects and advantages of the invention, such as arise in connection with carrying out the above noted ideas in a practical embodiment, will in part become apparent and in part be hereinafter stated, as the description of the invention proceeds.

15 The invention, therefore, comprises a garment hanger together with means for detachably holding a size tag in position in which it may be readily seen. The particular type of retaining means may vary with the particular type of hanger.

20 For a full and more complete understanding of the invention, reference may be had to the following description and accompanying drawings wherein:

25 Figure 1 is a perspective view of a garment hanger together with a size tag retainer that is applied thereto in accordance with the precepts of this invention.

30 Figure 2 is a transverse, vertical section taken about on the plane represented by the line 2—2 of Figure 1.

35 Figure 3 is a top plan view with the shank of the hook shown in section and is taken on an enlarged scale about on the plane represented by the line 3—3 of Figure 1.

40 Figure 4 is another perspective of the central portion of a hanger with a modified form of a size tag retainer applied thereto.

45 Figure 5 is a detailed section taken about on the plane represented by the line 5—5 of Figure 4.

Figure 6 is a top plan view with the shank of the hook shown in section and taken about on the plane represented by the line 6—6 of Figure 4.

50 Figure 7 is a view in front elevation of still another modification, and

55 Figure 8 is a horizontal section taken about on the plane represented by the line 8—8 of Figure 7.

Referring now to the drawing wherein like reference characters denote corresponding parts and

first more particularly to Figures 1, 2, and 3, a garment hanger is therein illustrated and shown as comprising an arcuate hanger bar 10 with the shank 11 of a hook 12 anchored thereto midway between the ends thereof in a well-known manner. The bar 10 ordinarily is of wood although it may be of any material. A size tag retainer is referred to in its entirety by the reference character R and is shown as being of U-shaped cross section defined by a rear wall 13, a bottom wall 14 and a front wall 15. The retainer R is a one piece integral unit that is made from an appropriate plastic having desired properties of transparency and flexibility. There are many of the cellulose acetates which fulfill these requirements, and there are also numerous other plastics now available on the market as such, which have the desired properties.

Upon referring to Figure 2, it will be seen that the rear wall 13 is in face to face engagement with one wall of the hanger bar 10. It may be permanently secured in this position by any appropriate adhesive or cement.

The front wall 15 is slightly spaced with respect to the other face of the bar 10 and side flanges shown at 16 and 17, extend from the side edges of the front wall 15 to the face of the bar 10.

A size tag which is represented by broken lines 18 is slipped in between the front wall 15 and the adjacent face of the bar 10. This size tag will be confined and held in position by the flanges 16 and 17. It is evident that the indicia on the tag 18 may be readily seen by a store attendant or prospective purchaser through the transparent wall 15. Obviously, this size tag 18 may be removed and replaced by another one whenever occasion demands.

In many instances, the shank 11 of the hook extends entirely through the bar 10 and will exhibit a tendency to slide downwardly into a somewhat awkward position. With the bottom wall 14 held against the bottom of the bar 10 by the side wall 13, this sliding action on the part of the shank 11 is prevented.

Referring now more particularly to Figures 4, 5, and 6, a slightly different type of tag retainer is therein illustrated. In this form of the invention, the bar 10 and shank 11 of the hook are the same as above described. The tag retainer is referred to in its entirety by the reference character T and is also made from an appropriate plastic having desired properties of transparency and flexibility.

The tag retainer is a one piece integral unit including a rear wall 19 that is formed with a bottom flange 20 which engages the bottom edge of the bar 10. This rear wall 19 is intended to snugly engage the rear face of the bar 10 and at its upper edge a top wall 21 is integrally joined thereto. This top wall 21 is formed with an aperture 22 which accommodates the shank 11 of the hook. The top wall 21 engages the top edge of the bar 10 and integrally joined to the front edge thereof is a front wall 23 which carries at its lower edge, a bottom flange 24 which overlies the flange 20 and which terminates in a turned back edge or bead 25.

This front wall 23 is spaced from the adjacent face of the bar 10 a sufficient distance to accommodate one of the size tags 18. The side edges of the front wall 23 carry inwardly turned flanges 26 and 27 which serve to confine the tag 18 therewithin.

Due to the flexible nature of the retainer T, it

may be fitted over the garment hanger in the manner illustrated and one of the tags 18 fitted beneath the front wall 23. Due to the transparent nature of this front wall, the indicia on the tag 18 may be readily seen. Just as in Figures 1, 2, and 3, the bottom flanges 20 and 24 serve to prevent sliding of the hook shank 11.

Referring now more particularly to Figures 7 and 8, a modified form of garment hanger is 10 therein illustrated. This garment hanger comprises two arms 28 and 29 which are made of an appropriate plastic and which meet at a central panel 30. The arms 28 and 29 of the panel 30 are integrally joined and the edges thereof are 15 provided with ribs 31 which offer increased rigidity. The central panel 30 is provided with a vertical embossment 32 which receives the shank 11 of the hook 12.

One or both of the opposite faces of the central panel 30 may be provided with a pair of complementary corner pockets 33 and 34 which also preferably are of plastic. These pockets 33 and 34 may either be separate pieces which are applied to the panel 30 after the latter has been 20 fashioned, by using an appropriate adhesive or they may be made integral with the central panel. A size tag represented by broken lines at 35 is 25 detachably held in position by a pair of these corner pockets.

While preferred specific embodiments of the invention are hereinbefore set forth, it is to be clearly understood that the invention is not to be limited to the constructions and materials illustrated and described, because various modifications of these details may be provided in putting the invention into practice within the purview of the appended claims.

What is claimed is:

1. In a garment hanger including a bar and a hook having a shank anchored to said bar substantially midway the ends thereof, a size tag retainer secured to said bar where said shank is secured thereto, said size tag retainer comprising a piece of transparent, flexible plastic shaped to provide a top wall having an opening receiving said shank, a rear wall integrally joined to the rear edge of said top wall, a front wall integrally joined to the front edge of said top wall and spaced from the front face of said hanger bar, and overlapping bottom flanges carried by said front and rear walls.

2. In a garment hanger including a bar and a hook having a shank anchored to said bar substantially midway the ends thereof, a size tag retainer secured to said bar where said shank is secured thereto, said size tag retainer comprising a piece of transparent, flexible plastic providing a top wall having an aperture receiving said shank, a rear wall integrally joined to the rear edge of said top wall and engaging the rear face of said bar, a front wall integrally joined to the front edge of said top wall and spaced from the front face of said bar, inwardly extending side flanges carried by said front wall, and overlapping bottom flanges carried by said front and rear walls.
